United States Patent Office.

JOHN ATWOOD, JR., OF PROVINCETOWN, MASSACHUSETTS.

Letters Patent No. 68,336, dated September 3, 1867.

IMPROVED RIG FOR SLOOPS AND SCHOONERS.

The Schedule referred to in these Letters Patent and making part of the same.

Be it known that I, JOHN ATWOOD, Jr., of Provincetown, in the county of Barnstable, and State of Massachusetts, have invented a new and improved Rig for Schooners, Sloops, and other sailing vessels; of which the following is a full, clear, and exact description, reference being had to the accompanying drawings, making a part of this specification, in which—

Figure 1 represents a vessel with my improvement applied, and

Figure 2 is a perspective view of my improvement on an enlarged scale.

The object of my invention is to provide a rig for a vessel carrying one or more masts, by which a large amount of sail may be spread in favorable weather, and which sail may be expeditiously reduced, so that the lower rigging only is used in the event of a storm, or in bad weather; and the invention consists in the employment of a secondary or additional mast, in connection with a lower mast, so arranged that it may be extended upwards on a line parallel with the lower mast, and there securely held in position; and when necessary the said secondary mast may be lowered, so that the lower end will be firmly fixed in or to the deck, and the upper end secured in position; and thus the two will form or serve as one mast, of great strength, capable of carrying the usual amount of lower rigging in any weather, however severe.

Referring to the drawings, fig. 1 represents a schooner with the additional mast elevated on the foremast, with its complement of sails, and in the rear mast it is lowered in position for stormy weather.

A A' represent the two lower masts, provided at their upper ends with cross-pieces C and caps D, the same being firmly secured to the lower masts. a a represent guides or stays, attached to the front portion of the cross-tree C, and, extending downwards, are firmly secured to the deck of the vessel. These guides may be made of ropes or rods. B represents a secondary or additional mast, passing through a hole in the cross-piece C and cap D, in front, as shown in fig. 2. On each side of the lower end of the additional mast B are attached metallic loops or eyes b, which encompass the guide-rods a, and slide upon the same, as the mast B is raised or lowered, to keep the same in proper position. The lower end of the mast B', when the same is lowered to the position as shown by the rear mast A', is fitted within an aperture in the deck, or otherwise firmly secured to the deck, and the upper end of the said mast is also firmly secured to the cap and cross-tree above. The ends of the cross-trees are also firmly secured to the sides of the vessel.

In favorable weather the additional mast B is raised to the position as shown in connection with the foremast, with all the necessary sails attached. In the event of a storm, or during severe weather, the additional mast is lowered, as shown at B', in connection with the rear mast, fig. 1, and the lower rigging only is used. The mast B may be raised and lowered by a windlass, or otherwise, and the operation of lowering may be performed very expeditiously in case of a sudden storm. When the mast B is lowered and made fast, as described, it serves to strengthen the stationary mast A, and the vessel is then enabled to carry the usual amount of sail below, without endangering the vessel or masts in the severest weather. The stationary and additional masts, when the latter are lowered, are separated from each other only a sufficient distance to admit of the free passage of the mast-hoops between them.

I am aware that the topmasts of sloops and schooners, and the top-gallant-masts of square-rigged vessels, have been arranged to be raised and lowered temporarily and partially upon the stationary masts; but this is no part of my invention.

What I claim as my invention, and desire to secure by Letters Patent, is—

1. In combination with the stationary mast A, the secondary or additional mast B, when the latter is so arranged as to be capable of being firmly fixed to the deck, and form a support to the stationary mast, or of being raised, so as to form a continuation of the said stationary mast, as and for the purpose specified.

2. I claim, in combination with the secondary mast B, the guides a a, the eyes b, and the cross-tree C, as described.

In testimony whereof I have signed my name to this specification in the presence of two subscribing witnesses.

JOHN ATWOOD, JR.
